Primary Examiner — Ryan Harvey(74) *Attorney, Agent, or Firm* — The Watson IP Group, PLC; Jovan N. Jovanovic(57) **CLAIM**

The ornamental design for a stationary bicycle, as shown and described.

DESCRIPTION

FIG. 1 of the drawings is a front, side, top perspective view of the stationary bicycle showing, in particular, the ornamental design thereof;

FIG. 2 of the drawings is a back, side, top perspective view thereof;

FIG. 3 of the drawings is a bottom, side, back perspective view thereof;

FIG. 4 of the drawings is a first side elevational view thereof;

FIG. 5 of the drawings is a second side elevational view thereof;

FIG. 6 of the drawings is a top plan view thereof;

FIG. 7 of the drawings is a bottom plan view thereof;

FIG. 8 of the drawings is a front elevational view thereof; and,

FIG. 9 of the drawings is a back elevational view thereof.

1 Claim, 9 Drawing Sheets(56)
